UNITED STATES PATENT OFFICE.

CHARLES N. CHADWICK, OF BROOKLYN, NEW YORK, ASSIGNOR TO ALICE A. CHADWICK, OF SAME PLACE.

DESIGN FOR A WAIST.

SPECIFICATION forming part of Design No. 23,033, dated February 6, 1894.

Application filed November 24, 1893. Serial No. 491,899. Term of patent 14 years.

To all whom it may concern:

Be it known that I, CHARLES N. CHADWICK, of Brooklyn, in the county of Kings and State of New York, have invented a new Design for 5 Waists; and I do hereby declare the following, when taken in connection with accompanying drawings and the letters of reference marked thereon, to be a full, clear, and exact description of the same, and which said drawing constitutes part of this specification, and represents a view of a waist complete embodying my design.

This invention relates to a design for waist, having special reference to the outer surface 15 of the back section of the same, and it consists in the conformation of the waist as shown in the accompanying illustration.

The waist consists of a body portion having a back-section A', and front sections A² 20 and A³ having the shape shown and is provided with arm openings B B; around the said arm openings and extending to the waist line are bands or straps C C, secured to the

outer surface of the body of the waist. Near the upper edge of the back section of the 25 waist and upon the outer surface is a band A, extending transversely from side to side, its lower edge substantially in line with the lower edge of the arm-openings B B, the said band terminating in and represented as overlapped by the said bands or straps C C. The band thus gives the appearance of a shoulder-brace by seeming to unite the shoulder-straps, as shown in the accompanying illustration. 30

35

I claim—

The design for a waist as herein shown and described.

In testimony whereof I have signed this specification in the presence of two subscribing witnesses. 40

CHARLES N. CHADWICK.
